UNITED STATES PATENT OFFICE.

WILLIAM GREGORY GIBBONS, OF EDINBURGH, SCOTLAND, AND FREDERICK JOHN BLAKE, OF BASSETT, ENGLAND, ASSIGNEES TO J. STONE & COMPANY LIMITED, OF DEPTFORD, ENGLAND.

HYDRAULIC BULKHEAD-DOOR APPARATUS.

1,090,784.

Specification of Letters Patent. Patented Mar. 17, 1914.

Application filed September 15, 1913. Serial No. 789,950.

To all whom it may concern:

Be it known that we, WILLIAM GREGORY GIBBONS and FREDERICK JOHN BLAKE, subjects of the King of Great Britain, and residing, respectively, at Viewpark, Russell Place, Trinity, Edinburgh, in the county of Midlothian, North Britain, and Beechcroft, Burgess street, Bassett, in the county of Hampshire, England, have invented new and useful Hydraulic Bulkhead-Door Apparatus, of which the following is a specification.

Bulkhead and like doors in ships are usually raised and lowered by power, or by hand mechanism, operating the doors through various forms of gearing. In the gearing there is in some cases a disconnectible locking device, such as a clutch or a ratchet and pawl, so that on withdrawing this device the door is freed and closes by its own weight.

We are aware that it has hitherto been proposed to release bulkhead doors by withdrawing a pawl from a rack on the door by means of a rod acting directly on the pawl, the rod being connected directly to and operated by a diaphragm or piston actuated by compressed air or water power. We are further aware that it has also been proposed to provide a system of combined hydraulic power and hand operated gearing for raising and lowering watertight doors for ships in which there is a clutch in the hand gear which is automatically withdrawn when the hydraulic gear is operating the door, the clutch being only controlled by the hydraulic door operating gear and not separately from the bridge. This invention however only relates to bulkhead and like doors which close by gravity when released and has for its object to provide improved and simple apparatus by means of which the clutches, pawls or the like in the door operating mechanism of all the doors on board a ship may be withdrawn from the bridge or other suitable position at a distance from the doors, either simultaneously, so that the doors may all be allowed to close at one time when desired; or separately so that any lesser number of the doors could be closed and the others left open.

The improved apparatus comprises essentially a usual disconnectible locking device

in each door operating gearing, means controlled by a spring and by a small hydraulic cylinder to operate the locking device, a single hydraulic cylinder at or near the transmitting station the ram or piston of which has a displacement equal to more than that of all the small rams or pistons, pipe connections putting each of the small cylinders in communication with the large cylinder, a valve or cock on each pipe connection, means for operating the large ram by power, or by hand, or by both power and hand an operating-fluid supply tank situated at some little height above the apparatus, a supply pipe connecting this tank with the large hydraulic cylinder, means for closing the supply pipe on the inward movement of the large ram and opening it on the outward movement thereof, and when power is used to operate the large ram, means for controlling the movement of the motor is also preferably employed. When the large ram is at the outer end of its cylinder the pressure in the pipe system is only that due to the head of operating fluid in the overhead tank. The system is thus kept fully charged, and any variation in the normal pressure due to leakage, contraction, or expansion is thereby corrected. To cause all the doors to close at one time the large ram is moved inward in its cylinder. A small movement inward of this ram cuts off the supply of fluid from the overhead tank so that the system is then shut off from this tank. On continued inward movement of the ram, pressure is at once transmitted to all the small cylinders, causing the rams thereof to so actuate the means operating the disconnecting device against the pull of the spring that all the devices are disconnected. All the doors are then free to close as hereinbefore described.

Should it be desired to close only some of the doors and leave the others open, the cock on the pipe connection leading to the receiving cylinders of the doors which it is desired to leave open is closed before the transmitting ram is operated.

In order that the invention and the manner or performing the same may be properly understood there are hereunto appended six sheets of explanatory drawings in which—

Figure 1, Sheet 1, is a sectional elevation

showing diagrammatically one example of the improved apparatus. Fig. 2, Sheet 2, is a sectional elevation, and Figs. 3 and 4 Sheet 3, are elevations at right angles to each other showing a second example of the transmitting part of the apparatus, while Fig. 5, Sheet 4, is an elevation showing a third example of that part of the apparatus; and a fourth example is shown in Fig. 6, Sheet 5, and Fig. 7, Sheet 6, these two figures being elevations at right angles to each other.

As shown in Fig. 1 of the drawings, the bulkhead door A is of usual form having on it a rack A¹ with which engages a pinion A² on a shaft A³ operated through worm and wormwheel gearing A⁴ by hand or power when it is desired to raise the door. On the wormwheel is one member A⁵ of a locking clutch, the other member A⁶ of which is movable endwise on the shaft A³. When the two parts A⁵, A⁶ of the clutch are engaged the door is held in its open position by the worm and wormwheel A⁴. On disengaging the movable part A⁶ of the clutch from the fixed part A⁵ the gearing is freed and the door descends by its own weight to its closed position. Its descent may be controlled by cataract cylinders if desired. The movable part A⁶ of each clutch has connected to it one end of a bellcrank lever B to which a spring B¹ is so attached that the two parts of the clutch are normally kept in engagement. A rod B² connects the lever B to the usual float device (not shown) which operates the lever so as to free the clutch upon the rise of water in the ship's hold and thus allow the door to close, as hereinbefore described, all in known manner.

In order that the locking clutch device A⁵, A⁶ in the door operating mechanism of all the doors on board a ship may be released from the bridge or other suitable position at a distance from the doors, either simultaneously so that the doors may all be allowed to close at one time when desired, or separately so that any lesser number of the doors could be closed and the others left open, according to the present invention each lever B is also connected by slotted links B³ to the ram of a small hydraulic cylinder B⁴. Pipe connections B⁵ put the interior of each of the small cylinders in communication with a port C in a single hydraulic cylinder C¹ at or near the transmitting station. The ram C² of this cylinder has a displacement equal to more than the joint displacement of all the small rams. Each pipe connection B⁵ is fitted with a valve or cock (not shown). An operating-fluid supply tank C³ is situated at some little height above the apparatus and connected by a pipe C⁴ with a port C⁵ in the cylinder C¹. The pipe C⁴ is fitted with a valve 65 casing D containing a valve D¹⁰ which is

closed by a spring D¹¹ on the inward movement of the large ram C² and is opened on the outward movement thereof by a cam-shaped tappet D¹² on a rod D¹ operated by a tappet crosshead D² on the ram, so that when the large ram C² is at the outer end of its cylinder as shown in Fig. 1 the tappet D¹² engages for example an external arm D¹³ on the outer end of a rock shaft D¹⁵ which has on its inner end, within the casing D, an arm D¹⁴ provided with a forked end engaging a lug on the valve stem and raises the latter against the action of the spring and opens the valve D¹⁰ so that the charging of the pipe system at a pressure 80 due to the head of operating fluid in the overhead tank C³ is insured. A stop cock C⁶ controls the supply from the tank C³, so that the operating fluid may be cut off from the cylinder C¹ when desired, and this cylinder is fitted with a relief valve C⁷ to prevent damage from excess pressure in the system.

To operate the large ram C² there is provided an electric motor (not shown) operating a worm D⁸ gearing with a worm wheel D⁹ on a short hollow shaft D⁵ turning in bearings formed for it in a carrying stool D⁶. The shaft D⁵ is internally screwed to receive the externally screwed end of a shaft 95 E passing through it. The opposite end of this shaft butts against one end of a second shaft E¹ carried with it on a supporting bracket E², the opposite end of this second shaft E¹ being connected to the large ram 100 C². On this second shaft is a rack E⁴ with which there gears a pinion E³ driven through multiplying gearing by a hand wheel E⁵.

When the motor is started the worm D⁸ and wormwheel D⁹ are so actuated that the 105 screwed shaft E is made to travel endwise in the direction which causes the rack shaft E¹ and large ram C², to which it is connected, to move inward. On a small inward movement of this ram, the valve D¹⁰, controlling the supply of fluid from the overhead tank C³, is free to close, so that the pipe system is then shut off from this tank. On continued inward movement of the ram C², pressure is at once transmitted to all the 110 small cylinders B⁴, causing the rams thereof to so actuate the levers B, operating the movable parts A⁶ of the clutches against the pull of the springs B¹, that all the clutches are freed. All the doors A are then free to 115 close as hereinbefore described.

If the cock on any of the pipe connections B⁵ is closed before the ram C² is operated the corresponding door or doors will remain open while the others are allowed to close. 120 When the doors A close, the motor is then stopped either by hand or automatically by an electric contact device, or a device operated, through suitable means, by the pressure in the system, as hereinafter de- 125 130

scribed. During the inward movement of the ram C^2 the handwheel E^5 and rack operating gearing are rotating idly.

When it is desired to withdraw the large ram C^2 , the motor is reversed so that the screwed shaft E is run to its extreme outward position. Then the gear operated by the handwheel E^5 is used to withdraw the ram. Or the screwed shaft E may be connected direct to the large ram C^2 so that the motor may be used to move the large ram in both directions, and the hand gear be dispensed with. Or again where the number of doors A is small and the power required to force the large ram C^2 inward consequently comparatively little, the motor and its gearing may be dispensed with, and the hand gear be used alone to operate the large ram.

Packed pistons may be substituted for the rams of the small receiving cylinders B^4 . Also instead of the ram C^2 in the transmitting cylinder C^1 , there may be used, according to the example shown in Figs. 2 to 4, a packed piston C^2 , the outlet port C in this case being formed near the outer end of the cylinder C^1 , also in this case there is substituted for the valve D of the previous example upper and lower ports C^5 , C^8 in the cylinder and connected by a pipe C^9 , the upper port C^5 being over-run by the piston to shut off the pipe system from the supply tank pipe C^4 shown by chain lines. The relief valve C^7 is similarly shown as being connected by a pipe C^{10} with the supply tank pipe C^4 .

The piston C^2 is formed on the upper end of a rack G (Fig. 2) working in the cylinder C^1 and gearing with a pinion G^1 on a spindle G^2 extending out through a stuffing box in the side of the cylinder. This spindle G^2 has on it a spurwheel G^3 gearing with a pinion G^4 on a second spindle G^5 which may be connected through a usual clutch device G^6 with a handwheel E^5 (loose on the spindle G^5) when it is desired to operate the transmitting piston C^2 by hand. The construction of transmitting plant in this example, thus far described, is similar to certain known forms of transmitting cylinders in telemotor gear.

In order to be able to operate the transmitting piston C^2 by spring power, according to this example, the piston has secured to it, one end of a rod H extending out through a stuffing box in the upper end of the transmitting cylinder C^1 . This rod has on its upper end a plunger H^1 working in a small cylinder H^2 open to the atmosphere and extending centrally within a pair of springs H^3 , H^4 arranged concentrically between a cross-head H^5 and a base H^6 carried on the cylinder C^1 , the small cylinder being screwed into an aperture formed through the crosshead H^5 . The springs H^3 , H^4 , are

separated by a guiding cylinder H^7 , and the crosshead has connected to it a pair of rods J^1 , J^2 extending down to and connected with plungers working in cataract cylinders J^3 , J^4 carried one on each side of the transmitting cylinder, these cylinders being provided for the purpose of checking the rapidity of action of the springs. In connection with each rod J^1 and J^2 there is provided a pair of links J^5 , J^6 each pair being hinged together at one end and pivoted at their opposite ends one to a pin J^7 on the cylinder C^1 and the other to a pin J^8 in the rods J^1 and J^2 . The lower link J^6 of each pair has on it a tail piece J^9 (Fig. 3) on which acts a spring-operated tappet K tending to force the links to one side of the center line (the left hand side in Fig. 3) and against cams K^1 , K^2 on a transverse shaft K^3 capable of being rocked by a handled lever K^4 . With the parts in the position shown in Figs. 3 and 4 the links act as struts and prevent the power of the springs H^3 , H^4 being exerted to pull the transmitting piston C^2 . When it is desired that the springs H^3 , H^4 should operate the piston C^2 , the shaft K^3 is rocked so as to cause the cams K^1 , K^2 to throw the hinged ends of the two pairs of links J^5 , J^6 to the opposite side of the center line from that in which they are shown in Fig. 3. The springs are then freed and the power stored in them acting through the crosshead H^6 , the small cylinder H^2 , the plunger H^1 , and the rod H connected to the transmitting piston C^2 operates that piston as desired. At the end of the stroke the links take up the position shown by dotted lines.

When it is desired to withdraw the transmitting piston C^2 , the clutch device G^6 is so operated as to cause the handwheel E^5 to be engaged with the spindle G^5 , and on turning that handwheel the piston is brought back through the gearing acting on the rack G and the springs H^3 , H^4 are pulled down. The links J^5 , J^6 are also then brought back to the position in which the tappet K forces them into the locking position.

According to the example shown in Fig. 5 the transmitting piston is connected with a piston in a steam cylinder L carried by a flanged bracket on the upper end of the transmitting cylinder C^1 . The inlet and exhaust passages L^1 , L^2 and ports of this cylinder L are controlled by a valve the spindle of which is connected by links L^3 with one arm of an operating bellcrank lever L^4 . The valve is so proportioned that when the ports are in mid position as shown both ports of the steam cylinder are open to the exhaust, and the transmitting piston may be operated by the handwheel gear as described in the second example hereinbefore described. On disconnecting the handwheel and moving the handled lever L^4 to the left, the

steam valve is so thrown that steam is admitted to the under side of the steam piston and this piston through its connecting rod then pulls up the transmitting piston to cause it to force the operating fluid through the pipe system to all or any of the small cylinders, as hereinbefore described. To force back the transmitting piston, the steam valve is so thrown as to admit steam to the upper side of the steam piston, the under side of that piston being then open to the exhaust. Or the steam valve may be brought to mid position and the transmitting piston withdrawn by the hand gear, as hereinbefore described.

As shown in Figs. 6 and 7 an electric motor M operates a spindle M¹ on which is a worm M² gearing with a worm wheel M³ on the handwheel spindle G⁵ the wormwheel being connected with the spindle by a clutch M⁴ the movable member of which is operated by levers M⁵ connected by links M⁶ with the handwheel clutch operating lever so that either the handwheel E⁵ or the motor may be thrown into gear to operate the transmitting piston as hereinbefore described.

A spring controlled plunger rod N projects through the top of the transmitting cylinder C', and is connected to a lever N', which controls the movement of a switch N² which in turn controls the supply of current to the motor. When the transmitting piston is at the end of its forcing stroke, it engages the lower end of the plunger rod N and forces the latter upward, thereby operating the lever N' so as to move the switch N² to cut off the current and stop the motor. Similarly to prevent damage from excess of pressure in the system, a pipe shown by a chain line N³ in Fig. 7, is led from the top of the transmitting cylinder C' to an accumulator N⁴ the ram N⁵ of which has connected to it a rod N⁶ to the upper end of which is connected one end of a lever N⁷ controlling the movement of a switch N⁸ which in turn controls the supply of current to the motor. Should pressure in the pipe system rise beyond a predetermined limit, the switch N⁸ is moved by the mechanism described so that the supply of current is cut off and the motor stopped. A spring P surrounding the rod N⁶ extends between an upper crosshead P¹ fixed to the upper end of carrying rods P² secured at their lower ends to a flange P³ on the accumulator N⁴, and a crosshead P⁴ free to travel upward on the carrying rods P² but limited in its downward travel by nuts P⁵ on the lower screwed ends of the rods P². During upward travel of the ram N⁵ nuts P⁶ on its rod N⁶ force up the free crosshead P⁴, and the spring P is compressed to such an extent that on the motor being stopped the reaction of the spring P will return the parts to

their first position on the pressure being reduced.

What we claim as our invention and desire to secure by Letters Patent of the United States is:—

1. A self-contained hydraulic power plant comprising a plurality of hydraulic mechanisms, a main hydraulic piston and cylinder, the displacement of which piston is at least equal to the sum of the liquid displacements required for the operation of said hydraulic mechanisms, a liquid supply tank connected to said cylinder, the supply of liquid to the cylinder being controlled in accordance with the movement of the piston, hand and power means for moving the piston, and means to control the power.

2. In a hydraulic power plant, a main hydraulic cylinder and piston, means for supplying pressure fluid to the cylinder, a spring connected with the piston, means for compressing the spring, means for locking the latter in its compressed position, means for releasing the locking means, and means for checking the expansion of the spring.

3. In a hydraulic power plant, a main hydraulic cylinder having an outlet at one end and an inlet port near its opposite end, a liquid supply connected with the inlet port, a piston in the cylinder adapted to close the inlet port during its forcing stroke, a spring connected with one end of the piston adapted to impart the forcing stroke thereto, and a rack and pinion connected with the other end of the piston to draw the latter against the action of the spring.

4. In a hydraulic power plant, a main hydraulic cylinder having pressure fluid inlet and outlet ports at opposite ends thereof, a piston in the cylinder controlling the inlet port, a rod connected to the piston, a spiral spring mounted at one end of the cylinder, means connecting the rod to the outer end of the spring, means to depress the spring to position the piston for its forcing stroke, means to lock the spring in its depressed position, means to release the locking means, and means to cushion the action of the spring during its expansion.

5. In a hydraulic power plant, a main hydraulic cylinder and piston, means for supplying pressure fluid to the cylinder, spring actuated mechanism for imparting the forcing stroke to the piston, means for retracting the piston against the action of the spring, means for locking the piston against the action of the spring, means for releasing the locking means and cataract cylinders connected with the spring actuated mechanism for cushioning the action of the spring.

6. In a hydraulic power plant, a main hydraulic cylinder and piston, mechanism for imparting a forcing stroke to the piston comprising concentric spiral springs mounted at one end of the cylinder, a connecting

5 cylinder extending centrally within the springs, a cross head connecting the outer ends of the connecting cylinder and springs, a plunger in the connecting cylinder, a rod connecting the plunger and piston, means to depress the spring to retract the piston, means to lock the spring depressed, and means to release the locking means.

10 7. In a hydraulic power plant, a main hydraulic cylinder and piston, mechanism for imparting a forcing stroke to the piston comprising concentric spiral springs mounted at one end of the cylinder, a connecting cylinder extending centrally within the springs, a cross head connecting the outer ends of the connecting cylinder and springs, a plunger in the connecting cylinder, a rod connecting the plunger and piston, means to depress the spring to retract the piston, means to lock the spring depressed, and means to release the locking means, cataract cylinders on each side of the main cylinders, and rods connecting the plungers of the cataract cylinders with the cross head.

15 20 25 8. In a hydraulic power plant, a main hydraulic cylinder and piston, mechanism for imparting a forcing stroke to the piston comprising concentric spiral springs

mounted at one end of the cylinder, a connecting cylinder extending centrally within the springs, a cross head connecting the outer ends of the connecting cylinder and springs, a plunger in the connecting cylinder, a rod connecting the plunger and piston, a rack on the piston, a pinion in mesh with the rack, hand operated mechanism for rotating the pinion to depress the springs, cataract cylinders on each side of the main cylinders, rods connecting the plungers of the cataract cylinders with the cross head, articulated links connected to the rods and main cylinder adapted to lock the springs in their depressed condition, means to hold the links in locking position, and means to move the links to release the springs.
